(57) **CLAIM**

The ornamental design for a trailer for carrying a motorcycle, as shown and described.

DESCRIPTION

FIG. 1 is a side elevational view of a trailer for carrying a motorcycle.

FIG. 2 is a top plan view of the trailer.

FIG. 3 is a rear elevational view of the trailer.

FIG. 4 is a front elevational view of the trailer.

FIG. 5 is a perspective view of the trailer; and,
FIG. 6 is a perspective view of the trailer folded upright for
storage.

The ornamental design is the configuration of the trailer
including a ramp mounted to the trailer rear to enable
loading of a motorcycle. In transit, the ramp is stored on the
trailer. The rear portion folds for upright storage.
